UNITED STATES PATENT OFFICE

JULES GLAENZER, OF NEW YORK, N. Y.

CIGARETTE BOX

Application filed July 21, 1927. Serial No. 207,508.

This invention relates to improvements in cigarette box constructions.

The primary object of this invention is the provision of a cigarette box construction including a plurality of cigarette boxes with novel means for interlocking the same, it being the intention that the boxes shall be used as individual trophies to be awarded as prizes for different athletic or other events, 10 with means by which the boxes may be interlocked together in such relation that they can be detachably held in row relation, so that access may be had to any particular box desired for removal of the contents thereof.

15 A further object of this invention is the provision of an improved cigarette box construction, including a plurality of cigarette boxes keyed in a novel relation in rigid relation in the same plane, the boxes being adaptable for use as individual trophies or prizes, and being detachable so that the same may be properly awarded as prizes for any particular event, and so related that if a particular club wins two or more of the cups, they can 25 be interlocked in such relation, and the trophies thus serve a useful purpose.

Other objects and advantages of this invention will be apparent during the course of the following detailed description.

30 In the accompanying drawing, forming a part of this specification, and wherein similar reference characters designate corresponding parts throughout the several views.

Figure 1 is a plan view, partly in section, 35 of three of the improved cigarette boxes held in an interlocked relation.

Figure 2 is a view looking from the hinged ends of the three boxes of Figure 1.

Figure 3 is a view looking at the assembled 40 boxes from the lid opening ends thereof.

Figure 4 is a view showing the individual boxes in a detached relation.

Figure 5 is an enlarged fragmentary sectional view taken through a key or joint 45 connection of a pair of the boxes.

Figure 6 is a perspective view of a novel key member adapted to hold a pair of boxes together.

In the drawing, wherein for the purpose of 50 illustration is shown only a preferred em-

bodiment of the invention, the letter A may generally designate the improved cigarette box construction, which may comprise end cigarette boxes B and C, and an intermediate cigarette box D, the same being held in a detachable interlocked relation by novel keys E.

The boxes B, C and D in the main are of the same construction, each of the same including a bottom wall 10, having side walls 12, an end wall 13 to which a closure 14 is hinged, 55 and an opposite end wall 15, illustrated in Figure 3 of the drawing. Thus the body portion of each box includes a bottom with side and end walls, and providing a compartment 20 therein which may be of a size to receive 60 cigarettes in any approved arrangement. The closure 14 for each of the boxes includes a top plate or wall 25 with depending side flanges 26, a hinge flange 27 at one end, and an opposite end flange 28 provided with a snap 65 29 to engage the top portion of the end wall 15, to hold the same in place according to well known box construction.

In the preferred construction the top portions of the side and end walls 12, 13 and 15 70 are marginally reduced, as shown at 35 in Figure 5 of the drawing, to receive the reduced depending flanges 26, 27 and 28 of the said box closure 14, so that the outer surfaces of the side and end flanges on the closure 75 30 or lid 14 will lie substantially flush with the outer surfaces of the adjacent walls of the body of the box.

The boxes are flat and relatively shallow, being adapted to support cigarettes in a horizontal position. The end boxes B and C are provided on the facing sides 12 thereof with bayonet slots 40, of T-shaped cross section, which slots extend longitudinally of the side walls 12, grooved thereinto, from exterior 80 thereof, extending from the rear walls 13 on which said slots outlet, to a point short of the front walls 15, so that the slots 40 terminate short of the walls 15.

Inasmuch as the intermediate box B will 85 have to lock at both sides, each of the side walls 12 thereof is provided with one of the T-shaped slots 40, of the same construction above mentioned, that is opening at ends on the hinge wall 13, and terminating in a dead 90 100

end just short of the wall 15 from which the box lid opens.

As to the interlocking assemblage of the boxes B, C and D, keys E are provided.

5 The keys E in cross section are of H shape, the same including strips 42 and 43 connected by a reduced web 44, the strips 42 and 43 being adapted for seating in the main portions of the grooves 40, with the web extending between the grooves of the adjacent boxes. As the grooves 40 open out at the ends 13 of the boxes, the boxes are placed with the outer surfaces of their walls 12 in abutting relation, as illustrated in Figure 5, and the key E is then slipped into the bayonet grooves 40, and the said key then holds them in an interlocked relation, as can readily be understood, against liability of detachment until one of the boxes is moved endwise with respect to 10 the other, to effect detachment of one or the other or both of the boxes.

As is illustrated in Figure 5 of the drawing, the boxes B, C and D are keyed together with the outer surfaces of the side walls 12 thereof in an abutting relation. The outer surfaces of the closure flanges 26, are set in slightly so as to provide a clearance 47 between adjacent boxes, which facilitates opening of the closures or lids 14, as can readily 15 be understood from the drawings.

As the boxes B, C, and D are preferably of the same size, they lie in the same plane, and are rigidly connected together and can only be detached by relative end sliding parallel 20 with the keys E. The closure 14 of course hinges in any approved manner, as by barrel hinges 50 on the walls 13 and 27, after the structure illustrated in the drawings.

The boxes in an interlocked relation provides a series of trophies which may be maintained in an assembled unitary condition, and provide a very much admired trophy for the club, or even for individual use, it being intended to engrave the individual boxes with 25 the particular event for which the box is offered as a prize. The interlocking connection is very compact, and indeed is invisible unless closely inspected. The plurality of the connected boxes may be used 30 to hold various grades and kinds of cigarettes, so that persons may select the desired brand of cigarette.

Various changes in the shape, size, and arrangement of parts may be made to the 35 form of invention herein shown and described, without departing from the spirit of the invention or the scope of the claims.

I claim:

1. In a cigarette box construction of the 40 class described a pair of cigarette boxes having side walls and individual compartments therefor, said side walls each being provided with facing key slots of T-shaped section, and a key member of substantially H shaped 45 cross section slidably fitting in said grooves to

hold the box in an interlocked detachable relation.

2. In a cigarette box construction of the class described end and intermediate cigarette boxes each including body portions with side 70 walls and individual closures therefor, the facing side walls of the end and intermediate boxes each being provided with grooves and keys to detachably interlock the boxes in a rigid individually detachable 75 relation.

3. In a cigarette box construction of the class described end and intermediate cigarette boxes including body portions with side and end walls and individual closures therefor, the facing side walls of the boxes being 80 externally grooved in a bayonet slot relation, and detachable keys for interfitting in said grooves to hold the boxes in assembled interlocked detachable relation. 85

4. In a cigarette box construction of the class described the combination of end and intermediate cigarette boxes each including individual bodies with individual compartments and individual closures therefor, the individual bodies having side walls, the facing side walls of the boxes being provided with longitudinally extending T-shaped slots disposed thereon, and detachable key members between the side walls of the intermediate box and the facing side walls of the end boxes interfitting in said slots, said key members being of an H-shaped cross section to interlock the boxes with the facing side walls in abutting engagement. 95

5. In a cigarette box construction of the class described end and intermediate cigarette boxes having individual compartments, the boxes having side walls, and keys detachably connecting the boxes in an interlocked relation with the side walls of the boxes in abutting engagement with the keys secreted therebetween. 100

6. In a cigarette box construction a pair of cigarette boxes having side walls provided with facing bayonet slots each opening at one end of its respective boxes and terminating in a dead end at the opposite end of the box, and a key detachably associated with said grooves in a concealed relation therein to 110 hold the boxes in an interlocked detachable rigid relation. 115

JULES GLAENZER.
